UNITED STATES PATENT OFFICE

2,416,856

BINDER

Hugo Thomsen, Washington, D. C.

Application March 26, 1945, Serial No. 584,883

6 Claims. (Cl. 281—19)

1

My present invention, in its broad aspect, has to do with improvements in binders or holders for memorandum books, pads, checks, perforated blank books and pads and the like, and the cover therefor may be fabricated of a single sheet of leather, or other material, or the cover may have pockets, or a lining, or a stitched strip to hold my device. My binder operates without a rod, or the like, passing through and between parts of the object bound, such as a memorandum book or pad, and eliminates the necessity of stitching the leaves of the pad together, or if the pad be stitched, my binder will operate upon it just as well as without stitches, and no rivets, screws, or the like, are used with my device, nor will it scratch a desk or the like.

In addition to the above, my binder is simple, sturdy and practical and is easily and quickly assembled without screws or rivets, and comprises but four simple and cooperating parts, namely, a hollow tubular bar to form the back, a flat strip with tongues locking to the back, and carrying a rod, and a clamping or gripping retainer to hold the pad or notebook, or the like, and which is mounted on the rod, and which is substantially U-shaped in cross section. With these simple and improved parts, my device is easily assembled and can be manufactured and sold at a relatively small price.

Other and equally important objects and advantages of my invention will be apparent from the following description and drawings, and changes may be made in size, shape, form, materials, and construction and arrangement of parts, and are within the purview of my broad inventive concept and the scope of the appended claims.

In the drawings, wherein I have illustrated a preferred embodiment of my invention—

Figure 1 is a view of my binder and cover opened up and holding a perforated pad;

Figure 2 is a section on the line 2—2 of Figure 1;

Figure 3 is a section on the line 3—3 of Figure 2;

Figure 4 is a detail perspective of an end of the flat strip with the attaching tongue and the raised support to receive an end of the rod;

Figure 5 is a vertical section showing the manner of assembling my device;

Figure 6 is a top plan view of the hollow tubular back;

Figure 7 is an end view of the hollow tubular back;

Figure 8 is an enlarged section showing the tongues of the flat strip locked to the hollow tubular bar by the upwardly bent end lips;

2

Figure 9 is a section on the line 9—9 of Figure 4;

Figure 10 is a modified form showing binding or attaching prongs struck out of the U-shaped clamping or gripping retainer, and

Figure 11 is a section on the line 11—11 of Figure 10.

In the drawings, wherein like characters of reference are used to designate like or similar parts throughout the several views:

- 10 The numeral 1 designates the cover to which is stitched as at 2, a lining 3. The cover has a pocket 4 and is folded medially between its side edges to form a front and back cover. At the medial point, or the point of fold, the lining 15 3 is slit top and bottom as at 5 to receive there-through between the cover and the lining my flat tubular back 6. My flat tubular back has extended lips 7 at the ends which are bent upwardly as shown in Figure 8. A flat strip 8 is placed over and parallel with the tubular back 6 and between the two is the material of the lining 3 as shown in Figure 8. The flat strip has reinforcing and stiffening corrugations 9, and upwardly, and over and downwardly bent end parts 10 forming supports for a rod 11, the ends of which pass through holes 10a in the supports 10. The downwardly bent portions 12 of parts 10 are extended to form tongues 13 which are bent inwardly into the tubular back—as shown 20 in Figure 5—to hold the strip in place on the back, with the lips 7 forming stops. A pad clamping and retaining device 14 is formed substantially U-shaped in cross section to go about the rod 11 and if desired, the retainer 35 may be soldered or spot-welded to the rod or simply clipped around the rod as shown in Figure 2 with the back and front, respectively 15 and 16 of the retainer instruck on opposed lines to form retaining beads 17 for the wire stitches 40 if the pad is thus fastened together. The notebook or pad (18) is frictionally retained between the back and front, 15 and 16 respectively—as shown in Figure 2. If desired, instruck tabs or retaining bars 19—see the modified 45 form of Figures 10 and 11—may be provided to lock the clamping and retaining member on the rod.

In assembling my device, the tubular back 6 is first applied to the cover, and the strip 8 50 engaged therewith and locked in place after which the rod 11 is engaged with the supports 10 to hold the retaining device and notebook in place with the rod 11 functioning as the fulcrum about which the notebook or the like, is 55 pivoted or turned.

From the foregoing, it is believed that the operation and advantages of my invention will be apparent, but it is again pointed out that interpretation of its scope should only be conclusive when made in the light of the subjoined claims.

I claim:

1. The invention as defined in claim 6 wherein the cover has a member attached thereto between which and the cover the back bar extends with the flat retaining strip above the member.

2. The invention as defined in claim 6 wherein in the bent end portions of the strip are formed with openings, the rod having its ends detachably and movably engaged in the openings.

3. The invention as defined in claim 6 wherein the rod is movably mounted in openings in the supports on the strip, and a clamping and retaining member is engaged with the rod and is substantially U-shaped in cross section and has side parts for frictionally retaining the pad therebetween.

4. The invention as defined in claim 6 wherein the clamping and retaining member has instruck parts engaging over the rod to hold the clamping and retaining member thereon.

5. The invention as defined in claim 6 wherein in the strip is formed with reinforcing corrugations, and wherein the bent end parts forming supports are substantially V-shaped in cross

section with the outer leg extended down at an angle and formed with a tongue.

5 6. A binder and holder for pads and the like, comprising a cover part, a hollow back bar engaged with the cover, a flat retaining strip attached at its ends to the back bar to hold the same in place on the cover, and provided with upwardly and downwardly bent end portions forming supports, tongues on said bent end portions, bent to engage in the ends of the back bar, lips at the ends of the back bar bent to form retainers for the tongues a rod carried between the supports, said rod being pivotally and detachably engaged with the supports and a 10 15 notebook retaining device carried on the rod.
